[57] ABSTRACT

A panel heater comprising a heat-generating element formed of a sheet of carbon fiber-containing paper and electrodes at both ends, layers of a synthetic resin and then aluminum foils laminated successively on both surfaces of said sheet of paper, and sheets of a synthetic resin further laminated on both surfaces of the aluminum foils. Electricity can be passed to the electrodes of the heat-generating element with good insulation.

FIG. 1

FIG. 2

FIG. 3

MOISTURE RESISTANT PANEL HEATER

BACKGROUND OF THE INVENTION

1. Field of the Invention

This invention relates to a panel heater for use in water or in a wet condition, especially in a fish tank for fish culture.

2. Description of the Prior Art

The panel heater for such purposes must meet a number of requirements, among which are;

1. It should have an output suited for the particular size of the water tank, and be free from current leakage.

2. Its surface temperature should not be too high (watt density).

3. It should not be corroded by sea water.

4. There should be no change in the resistance of the heat-generating element with the passage of time, and the element should generate a constant amount of heat.

5. The outer sheath of the heater should not burn when exposed to air.

6. The size of the heater should be moderate and easy to withdraw from the tank.

The conventional underwater heater which has a metal surface has a high watt density and a surface temperature of more than 200°C., and its temperature gradient in a water tank is steep. Therefore, it is unsuitable for fish culture. Furthermore, the metal coating on the surface is especially heavily corroded in a fish tank for sea fish, and can be used only for a short duration of time.

Commercially available vinyl resin coated wires are sometimes used as a heater for a fish tank. Officially, as underwater heaters, their outer coverings should be free from burning when subjected to a standard voltage in air, but are melted when tested in air. In order to prevent melting, it is necessary to increase their resistance by about four times, in which case, however, the wires become bulky and unsuitable for practical application.

On the other hand, the conventional panel heaters with laminated layers of synthetic resin films on both sides suffer from an increase in the resistance of the heating element by the influence of moisture which has permeated through the films as time passes, and a decrease in output cannot be avoided. Furthermore, when the heaters of this type are connected in water to an alternating current source, the worker standing on the ground feels leaked current when putting his hand into the water, although the leakage does not affect the fish in the tank. According to the Law for Regulating Electric Appliances, the leaked current should be less than 1 mA. Experiments show that in order to adjust the leaked current to less 1mA, the maximum area of the panel heater should be restricted to 700cm², and its output should be adjusted to less than 140 W. With such a panel heater, it is impossible to maintain a water tank having a capacity of 300 to 500 liters at a moderate temperature of 25° to 28°C.

SUMMARY OF THE INVENTION

The present invention provides a panel heater containing a carbon fiber-containing paper as a heating element, which is free from the above-mentioned defects as an underwater heater.

The main object of this invention is to provide an underwater heater for maintaining a fish tank for sea fish culture at a moderate temperature, which is safe and

usable for prolonged periods of time, that is, to reduce leakage of current by incorporating aluminum foil in a panel heater, and to prevent a change of the resistance of the heating element with the passage of time.

Still another object is to prevent the leakage of current at the current passing part of a panel heater.

BRIEF DESCRIPTION OF THE DRAWINGS

FIG. 1 is a plan view showing the structure of a moisture resistant panel heater of this invention;

FIG. 2 is an enlarged sectional view of a part of the panel heater shown in FIG. 1; and

FIG. 3 is a partly sectional plan view showing the current passing part of the panel heater of this invention.

DESCRIPTION OF THE PREFERRED EMBODIMENT

The structure of the panel heater of this invention will be described by reference to the accompanying drawings.

Referring to FIGS. 1 and 2, there is shown a panel heater consisting of a heating element 1, layers 2 and 2' of a synthetic resin such as polyethylene, aluminum foils 3 and 3', layers 4 and 4' of the above-mentioned synthetic resin, outer layers 5 and 5' of a synthetic resin such as a polyester, electrodes 6 and 6', and conducting wires 7 and 7' for passing electricity. Specifically, on both surfaces of the heating element 1 consisting of a sheet of carbon fiber-containing paper and electrodes 6 and 6' made, for example, of a copper wire gauze connected to both ends of the paper sheet are laminated the synthetic resin layers 2 and 2'. On both surfaces of the resin layers, the aluminum foils 3 and 3' are then laminated. Furthermore, on both surfaces of the aluminum foils, the synthetic resin layers such as polyethylene 4 and 4' and then the synthetic resin sheets such as polyester 5 and 5' are laminated successively. The heating element 1 is adapted to be heated by passing electricity through the electrodes 6 and 6'.

For example, when the panel heater is used in water or in a wet condition, it is necessary to take measures for preventing current leakage at terminals leading to the heating element in water or in a wet condition, as shown in FIG. 3. An extension of the electrode 6 of the panel heater is soldered to a core 10 of an exteriorly insulated conductor, and a polyethylene insulating layer 11 of the conductor is laminated by hot pressing to the polyethylene layer 2 and 2' which is an interlayer of the synthetic resin portion of the above heating element.

Then, a part of a polyvinyl chloride sheath 8 of the conductor is brought into contact with the edge 12 of the above laminated synthetic resin 5 and 5', and then, both of them are wrapped in contact with each other in a cloth, such as a felt or flannel 13, impregnated with an epoxy resin, and by curing the epoxy resin the, terminal portions of the panel heater are completed.

By this construction, the impermeability of the aluminum foils serves to avoid an increase in the resistance of the carbon fiber-containing paper, and hence a decrease in output. Furthermore, the presence of the aluminum foils contributes to the reduction of leaked current to about one-third as compared with a panel heater which does not include aluminum foils. Thus, the area of the panel heater can be increased by about three times.

The panel heater of this invention produces output suitable for a given fish culture tank, and is free from

current leakage and corrosion by sea water. It also prevents changes in the resistance of the heating element with the passage of time, and also burning of the outer layer during heat generation in air. It is flexible and can be formed into any desired shape, and moreover, a suitable temperature gradient in the fish tank can be provided by its suitable surface temperature. Thus, the panel heater of this invention can be effectively used with safety not only in water but also in a wet environment.

What we claim is:

1. A moisture resistant panel heater comprising a heating element consisting of a carbon fiber-containing paper sheet and electrodes on two opposite ends thereof, a layer of polyethylene laminated to both surfaces of said heating element, a layer of aluminum foil laminated to both outer surfaces of the polyethylene layers, sheets of a synthetic resin laminated to both outer surfaces of said aluminum foils, and further comprising extended portions of said electrodes soldered to a core of an insulated conductor having a polyethylene insulating layer and an outer sheath, said polyethylene insulating layer of said conductor melt-bonded to said polyethylene layers, and a felt impregnated with an

epoxy resin which is cured, said felt holding an edge of the outer synthetic resin layers of said heater and the outer sheath of said conductor.

2. A moisture resistant panel heater comprising a heating element consisting of a carbon fiber-containing paper sheet and electrodes on two opposite ends thereof, a layer of polyethylene laminated to both surfaces of said heating element, a layer of aluminum foil laminated to both outer surfaces of the polyethylene layers, a polyethylene layer laminated to both outer surfaces of said aluminum foils, and polyester sheets laminated to both outer surfaces of the last-mentioned polyethylene layers, and further comprising extended portions of said electrodes soldered to a core of an insulated conductor having a polyethylene insulating layer and an outer sheath, said polyethylene insulating layer of said conductor being melt-bonded to said first-mentioned polyethylene layers, and a felt impregnated with an epoxy resin which is cured, said felt holding an edge of the outer synthetic resin layers of said heater and the outer sheath of said conductor.

3. The panel heater of claim 1 wherein said electrodes are made of a copper wire guaze.
